UNITED STATES PATENT OFFICE.

NELSON R. STREETER, OF SYRACUSE, NEW YORK.

DESIGN FOR A VEGETABLE-MASHER.

43,064.

Specification for Design.

Patented Sept. 24, 1912.

Application filed July 12, 1912. Serial No. 709,074. Term of patent 7 years.

To all whom it may concern:

Be it known that I, NELSON R. STREETER, a citizen of the United States, residing at Syracuse, in the county of Onondaga and State of New York, have invented a new, original, and ornamental Design for Vegetable-Mashers, of which the following is a specification, reference being had to the accompanying drawing, forming part thereof.

The figure is a perspective view of a vegetable masher, showing my new design.

I claim:

The ornamental design for a vegetable masher as shown.

In testimony whereof, I hereunto affix my signature in the presence of two witnesses.

NELSON R. STREETER.

Witnesses:

FRED W. HATCH,
E. YOUNGBLOOD.
